CLAIM

The ornamental design for an air freshener diffuser, as shown and described.

DESCRIPTION

FIG. 1 is a left front top perspective view of an air freshener diffuser showing our design;

FIG. 2 is a right rear top perspective view of the air freshener diffuser of FIG. 1;

FIG. 3 is a right rear bottom perspective view of the air freshener diffuser of FIG. 1;

FIG. 4 is front elevational view of the air freshener diffuser of FIG. 1;

FIG. 5 is a rear elevational view of the air freshener diffuser of FIG. 1;

FIG. 6 is a top view of the air freshener diffuser of FIG. 1;

FIG. 7 is a bottom view of the air freshener diffuser of FIG.

1;

FIG. 8 is a left side view of the air freshener diffuser of FIG. 1; and,

FIG. 9 is right side view of the air freshener diffuser of FIG.

1.

The broken lines in the drawings show portions of the air freshener diffuser which form no part of the claimed design.

1 Claim, 5 Drawing Sheets
